UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE.

DESIGN FOR A RUG.

SPECIFICATION forming part of Design No. 27,684, dated September 21, 1897.

Application filed August 13, 1897. Serial No. 648,179. Term of patent 3½ years.

To all whom it may concern:

Be it known that I, ADOLPH PETZOLD, a citizen of the United States, residing at the city of Philadelphia, State of Pennsylvania, 5 have invented and produced a certain new and original Design for a Rug, of which the following is a full, clear, and exact description, reference being had to the accompanying drawing, forming a part of this specification.

10 My invention relates to the surface ornamentation of a woven rug; and it consists of the design therefor, as illustrated in said drawing, the distinguishing features comprising parallel rectangular line borders a and b and 15 between the same a series of floral figures composed principally of leaves c and flowers c'. The inner field center is ornamented with two similar figures d d', arranged one above the other and with the surrounding space filled in with floral and leaf figures. 20

I claim—

The design substantially as set forth.

In testimony whereof I have hereunto affixed my signature this 8th day of July, A. D. 1897.

ADOLPH PETZOLD.
